CLAIM

The ornamental design for a two-sided sign, as shown and described.

DESCRIPTION

FIG. 1 is a front perspective view of a two-sided sign showing my new design, with the broken lines showing for illustrative purposes only and forming no part of the claimed design;

FIG. 2 is a front elevational view thereof;

FIG. 3 is a right side elevational view thereof, with the opposite side being a mirror image;

FIG. 4 is a rear elevational view thereof;

FIG. 5 is a top plan view thereof; and,

FIG. 6 is a bottom plan view thereof.

FIG. 1

FIG. 2

FIG. 3

FIG. 5

FIG. 6

FIG. 4
